UNITED STATES PATENT OFFICE.

CHARLES HENRY HOPKINS, OF BUTLER, PENNSYLVANIA, ASSIGNOR OF FIFTY-ONE ONE-HUNDREDTHS TO NATIONAL MACHINERY CO., OF TIFFIN, OHIO.

BOLT-HEADER.

No. 873,750.

Specification of Letters Patent.

Patented Dec. 17, 1907.

Application filed February 23, 1907. Serial No. 358,873.

To all whom it may concern:

Be it known that I, CHARLES HENRY HOPKINS, a citizen of the United States, residing at Butler, in the county of Butler and State of Pennsylvania, have invented a new and useful Bolt-Header, of which the following is a specification.

This invention relates to heading machines for bolts, rivets and the like and more particularly to an improved die for making square or hexagon head machine bolts.

In the manufacture of bolts and rivets having heads of angular formation considerable difficulty has been experienced in producing a bolt having a perfect or symmetrical head free from the flash or fin which is usually formed around one side of the head during the upsetting process. This fin or flash is generally due to the excess or leakage of metal between the gripping dies and heading tool during compression and must be trimmed off in another machine before the bolts are ready for use.

The object of the present invention is to provide a die capable of producing a bolt or rivet the head of which is symmetrical in form and free from the objectionable flash or fin so that the bolt will not require any finishing after leaving the machine.

A further object of the invention is to provide a heading die having a tubular member or sleeve slidably mounted thereon and which in conjunction with the heading tool constitutes a matrix for the metal forming the head of the bolt.

A further object is to so arrange the sleeve on the heading tool that the initial longitudinal movement of the plunger will cause the sleeve to bear against the gripping dies and a further movement thereof actuate the heading tool to compress the metal in the matrix without liability of the metal flashing and forming a fin or flange on the bolt head.

A still further object of the invention is to generally improve this class of machines so as to increase their utility, durability and efficiency.

Further objects and advantages will appear in the following description, it being understood that various changes in form, proportions and minor details of construction may be resorted to within the scope of the appended claims.

In the accompanying drawings forming a part of this specification: Figure 1 is a hori-

zontal sectional view of a portion of a bolt heading or up-setting machine provided with a die constructed in accordance with my invention. Fig. 2 is a side elevation of the die detached. Fig. 3 is a longitudinal sectional view of the die.

Similar numerals of reference indicate corresponding parts in all of the figures of the drawings.

The improved die forming the subject matter of the present invention is principally designed for use in connection with bolt-heading machines of the single blow open die type but it will be understood that the invention is not limited to this particular type of machine as the same may be used with equally good results in connection with ordinary presses or solid die machines.

In the drawings 5 designates the frame of a standard type of bolt and rivet heading machine, 6 the longitudinally movable plunger and 7 the slide carrying the movable gripping die 8.

Secured in any suitable manner to the plunger 6 is the heading tool 9 the latter being provided with a shank 10 having an intermediate annular shoulder 11 defining a reduced extension 12, the face 13 of which is angular in formation and constitutes the die proper. Slidably mounted on the shank 10 is a tubular member or sleeve 14 which in conjunction with the die 13 forms a matrix for the reception of the heated bar or blank constituting the head of the bolt. The tubular member 14 is pivotally connected with the heading tool 10 by means of parallel links 15 one end of each of which is secured to an annular flange 16 in any suitable manner as by screws or rivets 17 while the opposite ends of the links are provided with elongated slots 18 for the reception of bolts or pins 19 carried by the tubular member and extending through said slots, as shown. The interior walls of the tubular member are hollowed out to form an enlargement 20 in which is seated a coiled spring 21 one end of which bears against the flange 16 while the opposite end thereof engages a shoulder 22 formed by the enlargement 20. It will thus be seen that the normal tendency of the coil spring 21 is to yieldably support the tubular member or sleeve 14 in advance of the die 13 so that the initial downward movement of the plunger 6 will cause the member 14 to bear against the stationary and movable dies 8 and 23 while a

further movement of the plunger will move the die 13 to operative position against the tension of the spring 20 and thus effectually compress the metal in the matrix without liability of the metal flashing or escaping between the dies and the tubular member and causing a fin or flange on the bolt head.

The longitudinal movement of the heading tool is limited by the flange 11 which engages 10 a stop shoulder 24 formed in the interior walls of the tubular member 14, as shown.

In operation the heated bar or stock is fed into the machine against the shearing blade or knife 25 and as the slide 7 is moved forward 15 the movable die 8 will grip the severed portion of the blank or stock and hold the same in alignment with the heading tool. As the plunger is moved in the direction of the work or stock the tubular member 14 will 20 bear against the co-acting dies and thus form a box or housing for the adjacent end of the stock so that when the die 13 is actuated against the tension of the coiled spring the metal in the matrix will be compressed and 25 assume the form of a finished bolt head. It will thus be seen that as the die moves forward to up-set the head of the bolt the flat bearing face 26 of the tubular member will come in contact with the gripping dies before 30 the metal in the blank or stock has an opportunity to flash or form a fin between the sleeve 14 and the gripping dies.

The movement of the dies 13 and sleeve 14 is so timed that the right amount of compression by the die 13 is secured to completely 35 form a bolt-head without tending to squeeze the hot metal between the faces of the member 14 and gripping dies.

The improved die may be used for making 40 square and hexagon head machine bolts, T head bolts, special track bolts and for various other purposes.

Having thus described the invention what is claimed is:

1. In a bolt heading machine, the combination with a heading tool, of a matrix slidably mounted on the heading tool, slotted links forming a connection between the matrix and heading tool, pins seated in the slots of the links, and means for yieldably supporting the matrix in advance of the heading tool. 45

2. A heading tool for up-setting machines including a die having its side walls off set to form a laterally extending flange, a tubular member 50 slidably mounted on the die and co-acting therewith to form a matrix, links secured to the flange and having their opposite ends provided with longitudinal slots, pins carried by the tubular member and seated in 55 said slots, and a spring interposed between the flange and tubular member for normally and yieldably holding the member in advance of the die.

3. A heading tool for up-setting machines 60 including a shank having one end thereof reduced to form a die having a solid angular face and provided with an intermediate stop shoulder, a flange extending laterally from the shank, a tubular member slidably mounted 65 on the shank and co-acting with the die to form a matrix, said tubular member being provided with an enlarged chamber and an annular shoulder, a spring seated in said chamber and having one end thereof bearing 70 against the adjacent wall of the chamber and its opposite end engaging the flange, a pair of links each having one end thereof secured to the flange and its opposite end slotted, and pins carried by the tubular member and engaging the slots in the links. 75

In testimony that I claim the foregoing as my own, I have hereto affixed my signature in the presence of two witnesses.

CHARLES HENRY HOPKINS.
